UNITED STATES PATENT OFFICE.

FREDERICK B. TOWNSEND, OF CHICAGO, ILLINOIS, ASSIGNOR OF ONE-HALF
TO W. H. MINER COMPANY, OF CHICAGO, ILLINOIS, A CORPORATION OF
ILLINOIS.

FRICITION DRAFT-RIGGING.

SPECIFICATION forming part of Letters Patent No. 734,009, dated July 21, 1903.

Application filed April 2, 1903. Serial No. 150,689. (No model.)

To all whom it may concern:

Be it known that I, FREDERICK B. TOWNSEND, a citizen of the United States, residing in Chicago, in the county of Cook and State 5 of Illinois, have invented a new and useful Improvement in Friction Draft-Rigging, of which the following is a specification.

My invention relates to mechanism for resisting buffing or tensile strains and absorbing 10 the shock thereof, the principal application to which my invention has been designed being to the art of railway draft-rigging appliances, and more particularly those of the friction type; and my invention has for 15 its primary object to provide an improved friction draft-rigging wherein shall be secured the combined advantages of simplicity and cheapness of construction, fewness of operating parts, economy of space occupied, directness and reliability in operation, and a 20 large and effectively-applied friction effect or resistance.

To this and other minor ends my invention consists in a mechanism of the character 25 named which has as its chief novel constructional characteristic the provision of a rotatable friction-block disposed with its axis of rotation at right angles to the buffing or pulling strains and one or more movable friction-blocks in frictional engagement with the 30 rotatable friction-block in association with means for causing a partial rotation of the rotatable friction-block when subjected to thrusts or strains.

It further consists, in connection with a draw-bar, a draw-bar extension, and spring, of a rotatable friction-block arranged with its axis transverse to the draw-bar, of one or more, preferably two, movable friction-blocks 35 connected with and operated by the draw-bar or its extension and frictionally engaging the rotatable friction-block, and means for causing the rotatable friction-block to turn as the draw-bar moves back and forth. 40 The movable friction-blocks which engage the rotatable friction-block may preferably also serve as followers for the spring or springs.

My invention also consists in the novel construction of parts and devices and in the

novel combinations of parts and devices herein shown or described.

The rotatable friction-block is preferably in the form of a cylinder. The means for causing the rotatable friction-block to rotate 55 in engagement with the movable friction-blocks may preferably consist of one or more lugs or projections on the stationary side plates or stop-castings in connection with corresponding notches or recesses in the rotatable friction-block. I prefer to utilize the movable friction-blocks as followers, as this reduces the number of parts and simplifies the construction.

In the accompanying drawings I have illustrated 65 the preferred form of my invention as embodied in a railway draft-rigging, and referring thereto—

Figure 1 shows a side elevation of a draft-rigging wherein my improvements are incorporated, certain transverse timbers of the frame appearing in cross-section and the side plate or stop-casting nearest the observer being removed. Fig. 2 is a top plan view of the same with the draft-rigging 70 mechanism shown partly in horizontal section. Fig. 3 is a transverse sectional view on the line 3 3 of Fig. 2. Fig. 4 is a detail in perspective of the rotatable friction-block or cylinder. Fig. 5 is a similar detail perspective of one of the movable friction-blocks which co-operates with the rotatable friction-block. Figs. 6 and 7 are detail perspectives 75 from different points of view of the side plates or stop-castings which support the friction-block and movable friction-blocks or followers, illustrating the integral lugs thereon, which engage co-operating notches in the end portions of the cylindrical friction-block to effect its partial rotation under the thrust of 80 the draw-bar thereon. Fig. 8 is a view similar to Fig. 3, illustrating a modification in respect to the location of the interengaging lugs and notches for rotating the rotatable friction-block or cylinder. Fig. 9 is a detail 85 illustrating a modified form of the rotatable friction-block or cylinder having a circumferentially-corrugated surface; and Fig. 10 is a top plan view similar to Fig. 2, illustrating 90 a modification in the positioning of the 95 springs. Fig. 11 is a detail illustrating a modified form of the rotatable friction-block or cylinder having a circumferentially-corrugated surface; and Fig. 10 is a top plan view similar to Fig. 2, illustrating 95 a modification in the positioning of the 100

rotatable friction-block or cylinder and a corresponding change in the location of its fulcrum-point or turning device.

Referring to the drawings, 10 designates the center sills, 11 the end sill, and 12 the draft-timbers, of an ordinary car-frame construction.

13 designates a buffing-block secured to the front face of the end sill and supporting the usual carry-iron 14, secured to the under side thereof, in which latter rests the draw-bar 15, provided at its outer end with the coupling-head 16 and at its inner end with the usual draw-bar extension 17, the same being preferably in the form of a strap or yoke.

18 designates a pair of metal plates, serving as side plates or stop-castings, securely bolted to the opposed inner faces of the draft-timbers and provided at their opposite ends with vertical abutments 19, constituting stops for the end followers, and an upper guide 26 and a lower guide 25, the latter being removable, as hereinafter more particularly described.

25 24 is the rotatable friction-block, arranged at right angles to the draw-bar or to its direction of movement, and 23 23 are a pair of movable friction-blocks having each a concave friction-face 23^a, engaging the convex friction-surface of the rotatable friction-block 24. The movable friction-blocks 23 23 are actuated by the draw-bar or its extension and are preferably located at the front and rear of the rotatable friction-block, so that 35 they may also serve as followers for the springs 20 21.

22 is the rear end follower. The springs 20 21 abut at one end against the rear end follower 22 and at their opposite end against the adjacent movable friction-block 23. The end friction-block 23 takes the pressure or thrust of the spring through the rotatable friction-block 24 and its companion friction-block 23, and said end friction-block 23 abuts as a follower against the stops 19 on the side plates or stop-castings 18, just as the follower 22 abuts against said stops 19 at the opposite end.

To cause the rotatable friction-block to turn or partially rotate between the movable friction-blocks 23 23, which engage it, as the draw-bar moves back and forth, I prefer to provide interengaging lugs or projections 25^a and notches 24^a on the side plates or stop-castings and on the periphery of the rotatable friction-block or cylinder 24, the lugs, stops, or projections 25^a being preferably formed on the side plates or stop-castings and the notches or recesses 24^a on the rotatable friction-block or cylinder 24. The lugs or 55 projections 25^a are preferably formed on the removable guides 25 of the side plates or stop-castings, as illustrated in Figs. 1 to 7, though the same may, if desired, be located on the upper guide 26, as illustrated in Fig. 8, or on the vertical face of the side plates or stop-castings, as illustrated in Fig. 10.

The rotatable friction-block or cylinder 24

and the movable friction-blocks or cylinders 23 and end follower 22 are all supported at their end portions by the removable guides 25 of the side plates or stop-castings, which are securely bolted thereto. The side plates or stop-castings 18, with their upper and lower guides 26 and 25 thus united, form, in effect, a pair of longitudinally-channeled cheek-plates 75 constituting guideways and supports for the movable elements of the mechanism.

The operation is as follows: Assuming the parts to be in the relative positions shown in Figs. 1 and 2, which are their normal positions when free from strains on the draw-bar, when a buffing strain or shock is imparted to the draw-bar, as in the coupling operation, the rear end of the draw-bar tends to thrust inwardly the outermost of the twin movable 80 friction-blocks or followers 23, which strain is transmitted to the cylinder 24, with a tendency to partially rotate the latter, owing to the fact that the thrust is imparted laterally of the cylinder, while the lowermost points of 85 its surface are held by the lugs or stops 25^a engaging the notches 24^a, and thus constituting a fulcrum or turning point about which the cylinder may roll. The thrust is transmitted thence to and through the innermost 90 movable friction-block or follower 23 to the springs 20 and 21; but the partial rotation of 95 the cylinder set up during this operation produces a large amount of friction between the contacting friction-faces of the movable friction-blocks or followers and the rotatable friction-block or cylinder, which absorbs a considerable portion of the strain, to that extent relieving the springs, especially in the way of saving them from the initial effects of severe 100 shocks, which have often proved fatal to the springs. In this connection it is noted that an additional result of this partial rotation of the cylinder on the movable friction-blocks or followers is to force the end portions of the outermost friction-block or follower hard up against the upper inwardly-extending horizontal flanges or guides of the stop-castings 18 and to simultaneously depress the end portions of the inner follower upon the guides or plates 25, 105 whereby additional friction is created between the followers and the stationary parts thus engaged by their end portions. It will also be observed that the lugs 25^a, extending, as they do, entirely across the upper faces of 110 the supporting-plates 25, notch up into their respective stop-castings 18, thereby giving additional strength to the lugs and increased rigidity and stability to the supporting-plates 115 themselves. In view of the strains imposed 120 upon the plates through the lugs by the cylinder the plates 25 beneath the lugs are preferably reinforced by integral ribs 25^b on the under surfaces thereof.

I have not herein shown my invention as 125 adapted to operate in connection with the tensile strains; but it will be obvious that these strains might also be provided for in a similar way by interposing between the out-

ermost friction-block or follower 23 and the inner end of the draw-bar a duplicate of the springs 20 and 21 and the end follower 22. In practice, as is well known, the pulling strains and shocks are not as severe and liable to injure or break the springs as are the buffering shocks and strains, and hence I have illustrated my invention only in connection with its principal intended application as a means to relieve the latter strains.

I am aware that it is old in a friction draft-rigging to provide a cylinder disposed with its axis of rotation longitudinally of the yoke and coincident with the direction of the strains, the surface of the cylinder frictionally engaging a fixed member embraced by the yoke. My present invention is distinguished in principle from such a construction in several important particulars. In the first place, the cylinder is disposed transversely of the yoke, whereby it occupies less of the space required by the followers and the springs. In the second place, the opposite surfaces of the cylinder directly engage the followers themselves, both the cylinder and the followers being capable of yielding bodily and by such action creating the desired frictional effect. Still again, the action of the cylinder on the followers, as above explained, automatically creates an auxiliary friction effect between the followers and their stationary supporting and guiding means.

It is evident that the device, as hereinabove described, and illustrated in Figs. 1 to 7, inclusive, of the drawings, might be considerably modified by the substitution of mechanically equivalent details and otherwise without departing from the spirit and substance of the invention. For instance, the lugs or fulerums that engage the cylinder might be formed on the under side of the overhanging horizontal flanges of the stop-castings 18, as shown at 25^m in Fig. 8, in which case the coöperating notches 24^m would of course be formed in the upper portions of the cylinder ends. Also the cylinder might be disposed with its axis vertical, as shown at 24^b in Fig. 10, between movable friction-blocks or followers 23^b, having vertically-concaved opposing faces embracing the cylinder, in which latter case also the lugs or fulerums would take the form of a single vertical lug 25^b on the inner face of one of the stop-castings, engaging a single elongated notch or groove 24^b, formed in and longitudinally of the opposed surface of the cylinder. In order to obtain an increased friction-surface and corresponding increased friction effect, the friction-cylinder may have its surface circumferentially corrugated, as shown at 24^c in Fig. 9, in which case the concave faces of the followers engaging the same would be correspondingly corrugated. It is also evident that the rotatable member 24 or 24ⁿ need not necessarily take the form of a cylinder, so long as it has friction-faces engaging the opposed friction-faces of the mov-

able friction-blocks or followers 23. Still further detail changes would readily suggest themselves to the mind of the mechanic 70 skilled in this art, and all such modifications I regard as within the purview of my invention.

While I have herein shown and described my invention as embodied in a draft-rigging 75 for railway-cars and contemplate that such will constitute its principal application, yet it is evident that the principle and substantial mechanical features thereof might be advantageously employed in any other mechanism 80 designed to resist buffering or tensile strains.

I claim—

1. In a friction draft-rigging the combination with a draw-bar, draw-bar extension and spring, of a rotatable friction-block trans- 85 verse to the draw-bar, and a pair of movable friction-blocks in frictional engagement therewith, substantially as specified.

2. In a friction draft-rigging the combination with a draw-bar, draw-bar extension and spring, of a rotatable friction-block trans- 90 verse to the draw-bar and a movable friction-block in frictional engagement therewith, substantially as specified.

3. In a friction draft-rigging the combination with a draw-bar, draw-bar extension and spring, of a rotatable friction-block trans- 95 verse to the draw-bar, a pair of movable friction-blocks in frictional engagement therewith, and means for causing said rotatable 100 friction-block to turn as the draw-bar moves, substantially as specified.

4. In a friction draft-rigging the combination with a draw-bar, draw-bar extension and spring, of a rotatable friction-block trans- 105 verse to the draw-bar and a movable friction-block in frictional engagement therewith, and means for causing said rotatable friction-block to turn under movement of the draw-bar, substantially as specified. 110

5. In a friction draft-rigging the combination with a draw-bar, spring, and a pair of side plates or stop-castings, of a rotatable friction-block arranged transverse to the draw-bar and a pair of movable friction-blocks, 115 and interengaging devices on the rotatable friction-block and stationary stop-casting for causing the rotatable friction-block to turn, substantially as specified.

6. In a friction draft-rigging the combination with a draw-bar, draw-bar extension and spring, a pair of side plates or stop-castings having each end abutments to limit the movement of the draw-bar, and upper and lower guides, of a rotatable friction-block, having 125 a device engaging a device on the stationary stop-casting to rotate said friction-block, and a friction-block movable with the draw-bar and engaging said rotatable friction-block, substantially as specified. 130

7. In a friction draft-rigging the combination with a draw-bar, draw-bar extension, spring, and a pair of side plates or stop-castings having each end abutments to limit the

movement of the draw-bar, and upper and lower guides, of a rotatable friction-block, having a device engaging a device on the stationary stop-casting to rotate said friction-block, and a pair of friction-blocks movable with the draw-bar, and engaging said rotatable friction-block, substantially as specified.

8. The combination with a draw-bar, draw-bar extension and spring, of a pair of side plates or stop-castings having end abutments, and upper and lower guides for the followers, of a rotatable friction-block transverse to the draw-bar, and a pair of followers having curved friction-faces engaging the curved friction-surface of said rotatable friction-block, substantially as specified.

9. The combination with a draw-bar, draw-bar extension and spring of a pair of side plates or stop-castings having end abutments, and upper and lower guides for the followers, of a rotatable friction-block transverse to the draw-bar, and a pair of followers having curved friction-faces engaging the curved friction-surface of said rotatable friction-block, and means for causing the rotatable friction-block to turn as the draw-bar moves, substantially as specified.

10. In a mechanism for resisting buffing or tensile strains and absorbing the shock thereof, the combination with an endwise-movable bar, of a rotatable block having a convex friction-surface disposed with its axis of rotation across the path of movement of said bar, a follower having a concave friction-face engaging said rotatable friction-block, and a stop engaging the peripheral portion of said friction-block whereby a lateral thrust on the latter causes a partial rotation thereof and a relative sliding movement between the frictionally-engaging curved surfaces of said friction-block and follower, substantially as specified.

11. In a mechanism for resisting buffing or tensile strains and absorbing the shock thereof, the combination with an endwise-movable bar, of a rotatable block having a convex friction-surface disposed with its axis of rotation across the path of movement of said bar, a follower having a concave friction-face engaging said rotatable friction-block, an elastic backing for said follower, and a stop engaging the peripheral portion of said friction-block whereby a lateral thrust on the latter causes a partial rotation thereof and a relative sliding movement between the frictionally-engaging curved surfaces of said friction-block and follower, substantially as specified.

12. In a mechanism for resisting buffing or tensile strains and absorbing the shock thereof, the combination with an endwise-movable bar, of a rotatable block having on opposite sides thereof convex friction-surfaces disposed with its axis of rotation across the path of movement of said bar, a follower having a concave friction-face engaging said rotatable

friction-block between the latter and the end of the bar, another similar follower engaging said rotatable friction-block on its opposite side, an elastic backing for said last named follower, and a stop engaging the peripheral portion of said friction-block whereby an endwise thrust of the bar causes a partial rotation of said friction-block and a relative sliding movement between the frictionally-engaging curved surfaces of the friction-block and the followers, substantially as specified.

13. In a draft-rigging mechanism, the combination with a draw-bar and its yoke, of a rotatable friction-cylinder disposed within and transversely of said yoke, a pair of followers having concave faces frictionally engaging opposite sides of said cylinder, an elastic backing for one of said followers, fixed abutments for the other follower, and a pair of fixed plates underlying and supporting the end portions of said cylinder and followers, said plates having stops engaging and co-operating with the peripheral portion of said cylinder, substantially as specified.

14. In a draft-rigging mechanism, the combination with a draw-bar and its yoke, of a rotatable friction-cylinder disposed within and transversely of said yoke, a pair of followers having concave faces frictionally embracing said cylinder on opposite sides thereof, a draft and buffing spring backing one of said followers, and end followers backing said spring, and a pair of oppositely-disposing longitudinally-channelled cheek-plates secured to the draft-timbers and constituting ways and supports for the ends of said cylinder and followers, said cheek-plates having fixed abutments for the followers and also means to engage and hold an eccentric part of the cylinder to cause a partial rotation of the latter within the followers when subjected to lateral thrusts, substantially as specified.

15. In a draft-rigging mechanism, the combination with a draw-bar and its yoke, of a rotatable friction-cylinder disposed within and transversely of said yoke, said cylinder having a pair of peripheral notches in its end portions, respectively, a pair of followers having concave faces frictionally embracing said cylinder on opposite sides thereof, a draft and buffing spring backing one of said followers, an end follower backing said spring, and a pair of oppositely-disposed longitudinally-channelled cheek-plates secured to the draft-timbers and receiving the ends of said cylinder and followers, said cheek-plates having fixed end abutments for the followers and intermediate inwardly-extending lugs engaging said peripheral notches of the cylinder, substantially as specified.

FREDERICK B. TOWNSEND.
